(57) **ABSTRACT**

A fixing unit includes a rotary member, a pressure member configured to form a fixing nip, a heater disposed in an internal space of the rotary member, the heater including a substrate, and a heating element provided on the substrate and configured to heat the rotary member by being energized, a heater holder configured to hold the heater, and a heat conducting member disposed between the heater and the heater holder. The fixing nip conveys the sheet in a direction parallel to a short direction perpendicular to a longitudinal direction of the heater. The heater includes a protrusion extending toward the heater holder from a surface, of the heater, provided on a side opposite to the fixing nip. The protrusion faces the heat conducting member in the longitudinal direction and is disposed so as not to overlap the heat conducting member as viewed in the short direction.

FIXING UNIT AND IMAGE FORMING APPARATUS

BACKGROUND OF THE INVENTION

Field of the Invention

The present invention relates to a fixing unit that fixes a toner image on a sheet and an image forming apparatus including the same.

Description of the Related Art

JP 2017-049618 A proposes a fixing unit that fixes a toner image onto a sheet, the fixing unit including a cylindrical film, a heater contacting the film, a support member supporting the heater, and a pressure roller forming a nip portion together with the heater via the film. A heat conducting member having high heat conductivity is attached to a surface of the heater opposite to the surface contacting the film, and the heat conducting member levels out the temperature of the heater in the longitudinal direction. The heat conducting member repeatedly expands and contracts as the temperature of the heater changes, which causes a positional deviation of the heat conducting member in the longitudinal direction with respect to the heater. JP 2017-049618 A proposes a configuration in which the heat conducting member is locked by the support member by providing a bent portion in the heat conducting member and inserting an outer portion of the bent portion into a hole of the support member.

Further, JP 2022-102905 A proposes a fixing unit including a heater having a protrusion on a back surface thereof and a heat conducting member having a groove to be fitted to the protrusion. The protrusion of the heater and the groove of the heat conducting member are fitted to each other to restrict a movement of the heat conducting member in the longitudinal direction with respect to the heater.

In JP 2017-049618 A and JP 2022-102905 A, a positional deviation of the heat conducting member is suppressed by fitting the bent portion or the groove of the heat conducting member to the support member or the heater. However, when the temperature of the bent portion or the groove of the heat conducting member becomes high, excessive thermal expansion may occur in the bent portion and the groove in the fitted state, and the heat conducting member may be deformed. In addition, if the heat conducting member is subjected to bending processing or punching processing, the heat conducting member may be deformed or damaged when the heat conducting member thermally expands due to residual stress resulting from the processing.

SUMMARY OF THE INVENTION

According to one aspect of the present invention, a fixing unit includes a rotary member having a cylindrical shape, a pressure member configured to form a fixing nip that fixes a toner image onto a sheet together with the rotary member, a heater disposed in an internal space of the rotary member, the heater including a substrate, and a heating element provided on the substrate and configured to heat the rotary member by being energized, a heater holder configured to hold the heater, and a heat conducting member disposed between the heater and the heater holder. The fixing nip conveys the sheet in a direction parallel to a short direction perpendicular to a longitudinal direction of the heater. The heater includes a protrusion extending toward the heater

holder from a surface, of the heater, provided on a side opposite to the fixing nip. The protrusion faces the heat conducting member in the longitudinal direction and is disposed so as not to overlap the heat conducting member as viewed in the short direction.

Further features of the present invention will become apparent from the following description of exemplary embodiments with reference to the attached drawings.

10 BRIEF DESCRIPTION OF THE DRAWINGS

FIG. 1 is a schematic diagram illustrating an image forming apparatus according to a first embodiment.

FIG. 2 is a cross-sectional view illustrating a fixing unit.

15 FIG. 3 is a cross-sectional view illustrating a cross section parallel to a longitudinal direction of a peripheral configuration of a heater.

FIG. 4A is a cross-sectional view illustrating a cross section taken along line CS1-CS1 illustrated in FIG. 3.

20 FIG. 4B is a cross-sectional view illustrating a cross section taken along line CS2-CS2 or line CS3-CS3 illustrated in FIG. 3.

FIG. 5A is a plan view illustrating a heat conducting member and a protrusion according to the first embodiment.

25 FIG. 5B is a plan view illustrating a modification of the protrusion.

FIG. 5C is a plan view illustrating another modification of the protrusion.

FIG. 6 is a cross-sectional view for explaining thermal 30 expansion of a heater and a heat conducting member.

FIG. 7 is a graph illustrating changes in lengths of gaps in the longitudinal direction when the heater and the heat conducting member thermally expand.

FIG. 8 is a cross-sectional view illustrating a cross section 35 parallel to the longitudinal direction of a peripheral configuration of a heater according to a first modification of the first embodiment.

FIG. 9A is a plan view illustrating a protrusion according to a second modification of the first embodiment.

40 FIG. 9B is a plan view illustrating a modification of the protrusion.

FIG. 9C is a plan view illustrating another modification of the protrusion.

FIG. 10A is a front view illustrating a front surface of a 45 heater according to a second embodiment.

FIG. 10B is a front view illustrating a back surface of the heater.

FIG. 11 is a cross-sectional view illustrating a fixing unit.

FIG. 12 is a front view illustrating the back surface of the 50 heater in a state where the heat conducting member is disposed on the heater.

FIG. 13 is a cross-sectional view illustrating a cross section taken along line 13A-13A of FIG. 12.

FIG. 14 is a front view illustrating a back surface of a 55 heater according to a first modification of the second embodiment.

FIG. 15 is a cross-sectional view illustrating a cross section taken along line 15A-15A of FIG. 14.

FIG. 16 is a front view illustrating a back surface of a 60 heater according to a second modification of the second embodiment.

FIG. 17 is a cross-sectional view illustrating a cross section taken along line 17A-17A of FIG. 16.

FIG. 18A is a front view illustrating a front surface of a 65 heater according to a third embodiment.

FIG. 18B is a front view illustrating a back surface of the heater.

FIG. 19 is a front view illustrating the back surface of the heater in a state where a heat conducting member is disposed on the heater.

FIG. 20 is a cross-sectional view illustrating a cross section parallel to the longitudinal direction of a peripheral configuration of the heater.

FIG. 21 is a front view illustrating a back surface of a heater according to a first modification of the third embodiment.

FIG. 22 is a front view illustrating the back surface of the heater in a state where the heat conducting member is disposed on the heater.

FIG. 23 is a front view illustrating a back surface of a heater according to a second modification of the third embodiment.

FIG. 24 is a front view illustrating the back surface of the heater in a state where a heat conducting member is disposed on the heater.

FIG. 25 is a cross-sectional view illustrating a cross section parallel to the longitudinal direction of a peripheral configuration of the heater.

FIG. 26 is a perspective view illustrating a heater holder according to a fourth embodiment.

FIG. 27A is a plan view illustrating a bonding portion.

FIG. 27B is a cross-sectional view illustrating a cross section taken along line 27B-27B of FIG. 27A.

FIG. 27C is a cross-sectional view illustrating a cross section taken along line 27C-27C of FIG. 27A.

FIG. 28A is a plan view illustrating a bonding portion according to a first modification of the fourth embodiment.

FIG. 28B is a plan view illustrating an oval bonding portion.

FIG. 28C is a plan view illustrating a square bonding portion.

FIG. 28D is a plan view illustrating a rectangular bonding portion.

FIG. 28E is a plan view illustrating another rectangular bonding portion.

FIG. 29A is a plan view illustrating a bonding portion according to a second modification of the fourth embodiment.

FIG. 29B is a cross-sectional view illustrating a cross section taken along line 29B-29B of FIG. 29A.

FIG. 29C is a cross-sectional view illustrating a cross section taken along line 29C-29C of FIG. 29A.

FIG. 29D is a cross-sectional view illustrating a cross section taken along line 29D-29D of FIG. 29A.

FIG. 30A is a plan view illustrating a bonding portion according to a third modification of the fourth embodiment.

FIG. 30B is a cross-sectional view illustrating a cross section taken along line 30B-30B of FIG. 30A.

FIG. 30C is a cross-sectional view illustrating a cross section taken along line 30C-30C of FIG. 30A.

FIG. 30D is a cross-sectional view illustrating a cross section taken along line 30D-30D of FIG. 30A.

DESCRIPTION OF THE EMBODIMENTS

First Embodiment

Overall Configuration of Image Forming Apparatus

First, a first embodiment of the present invention will be described. FIG. 1 is a schematic diagram illustrating an image forming apparatus 100. The image forming apparatus 100 according to the first embodiment is an electrophotographic laser beam printer. As illustrated in FIG. 1, the image forming apparatus 100 includes a feed cassette 35

provided to be insertable into and removable from a main body of the image forming apparatus 100, and a feed roller 10. The image forming apparatus 100 includes an image forming unit 36 that forms an image (a toner image) on a sheet P fed by the feed roller 10, a fixing unit 6, and a sheet discharge roller pair 9. In the present embodiment, the sheet as a recording material includes a sheet such as paper or an envelope, a plastic film such as a sheet for an overhead projector (OHP), cloth, or the like.

When an image formation command is output to the image forming apparatus 100, an image formation process is started by the image forming unit 36 based on image information input from an external computer connected to the image forming apparatus 100, an image reading device connected as an option, or the like. The image forming unit 36 includes a process cartridge including a photosensitive drum 1, a charging roller 2, a developing roller 4, a cleaning blade 7, etc., a laser scanner 33, and a transfer roller 5. The photosensitive drum 1 is rotated in a direction indicated by an arrow r1 by a driving force transmitted from a driving motor (not illustrated).

The image forming apparatus 100 is provided with a video controller 31 that converts image information input from an external personal computer or the like into image creation information. The laser scanner 33 receives a light emission instruction from a control unit 32 based on the image creation information received from the video controller 31, and irradiates the photosensitive drum 1 with laser light L. At this time, the photosensitive drum 1 is charged in advance by the charging roller 2, and an electrostatic latent image is formed on the photosensitive drum 1 when irradiated with the laser light L. Thereafter, the electrostatic latent image is developed by the developing roller 4 to form a toner image on the photosensitive drum 1.

In parallel with the above-described image formation process, sheets P stacked on the feed cassette 35 are sent out by the feed roller 10. The sheets P fed by the feed roller 10 are conveyed by a conveyance roller pair 37 toward a transfer nip NT formed by the photosensitive drum 1 and the transfer roller 5. By applying a transfer bias to the transfer roller 5, the toner image formed on the photosensitive drum 1 is transferred to the sheet P at the transfer nip NT. The toner remaining on the photosensitive drum 1 is collected by the cleaning blade 7.

The sheet P to which the toner image has been transferred by the transfer nip NT is heated and pressurized by a fixing nip NF of the fixing unit 6 to fix the toner image. Then, the sheet P onto which the toner image is fixed is discharged to a sheet discharge tray 38 by the sheet discharge roller pair 9.

Configuration of Fixing Unit

Next, a configuration of the fixing unit 6 will be described with reference to FIG. 2. FIG. 2 is a cross-sectional view illustrating the fixing unit 6. As illustrated in FIG. 2, the fixing unit 6 includes a fixing film unit 19, a pressure roller 17, etc. The fixing film unit 19 is pressed toward the pressure roller 17 by a pressure unit (not illustrated) to form the fixing nip NF together with the pressure roller 17. Note that the pressure roller 17 may be pressed toward the fixing film unit 19. The sheet P holding an unfixed toner image T on an upper surface thereof is introduced into the fixing nip NF by conveyance in a sheet conveyance direction p0, and is heated and pressurized at the fixing nip NF to fix the unfixed toner image.

The fixing film unit 19 includes a fixing film 13 having flexibility and formed in a cylindrical shape, and a heater 11 contacting an inner surface of the fixing film 13 to heat the

fixing film 13. Further, the fixing film unit 19 includes a heater holder 12 holding the heater 11, and a heat conducting member 18 disposed between the heater 11 and the heater holder 12. The fixing film 13 serving as a rotary member and a film is rotatable in a direction indicated by an arrow r13 while being in contact with the sheet P conveyed in the sheet conveyance direction p0. Note that, instead of the fixing film 13, an endless belt having flexibility or the like may be used. The heater 11 nips the fixing film 13 together with the pressure roller 17.

The pressure roller 17 serving as a pressure member has a metal core and a rubber layer, and abuts on an outer circumferential surface of the fixing film 13. It can also be said that the pressure roller 17 forms the fixing nip NF that nips the sheet P during conveyance together with the heater 11 via the fixing film 13. The pressure roller 17 is driven to rotate in a direction indicated by an arrow r17 by a motor (not illustrated) via a gear. When the pressure roller 17 rotates, the fixing film 13 rotates following the rotation of the pressure roller 17.

Each member constituting the fixing unit 6 extends in a direction perpendicular to the sheet conveyance direction p0 and a thickness direction TD of the sheet P, that is, a direction from the front to the back in FIG. 2 as a longitudinal direction LD (see FIG. 3). The dimension in the longitudinal direction LD of each member constituting the fixing unit 6 is set to correspond to a size of a sheet P allowed to pass through the fixing unit 6, and is set to a length corresponding to even the longitudinal feeding of LTR size sheets (215.9 mm×279.4 mm) in the fixing unit 6 according to the present embodiment. The dimension of each member in the longitudinal direction LD will be described in detail below. In addition, a direction perpendicular to the longitudinal direction LD and the thickness direction TD is defined as a short direction SD (see FIG. 4A), and the short direction SD is a direction parallel to the sheet conveyance direction p0 of the sheet P at the fixing nip NF.

Peripheral Configuration of Heater

Next, a detailed peripheral configuration of the heater 11 will be described. FIG. 3 is a cross-sectional view illustrating a cross section parallel to the longitudinal direction of a peripheral configuration of the heater 11. FIG. 4A is a cross-sectional view illustrating a cross section taken along line CS1-CS1 illustrated in FIG. 3. FIG. 4B is a cross-sectional view for explaining protrusions 11d and 11e to be described below, and is a cross-sectional view illustrating a CS2-CS2 cross section or a cross section taken along line CS3-CS3 illustrated in FIG. 3. Note that, in each of the drawings, an upper side of a figure in the drawing is described as a back surface of a member, and a lower side of a figure in the drawing is described as a front surface of a member. In addition, for convenience of explanation, it is illustrated in the drawings that each member is developed, but the members from the heater holder 12 to the fixing film 13 are formed to tightly adhere to each other in the actual fixing unit 6 as illustrated in FIG. 2.

As illustrated in FIG. 3, the heater 11 includes a substrate 11a, a resistive heating element 11b serving as a heating element, and a protective layer 11c, and is disposed in an internal space of the fixing film 13. The substrate 11a is made of a highly insulating ceramic substrate such as alumina (aluminum oxide) or AlN (aluminum nitride), or a heat-resistant resin substrate such as polyimide. The resistive heating element 11b is obtained by printing a heat generating paste layer of Ag/Pd (silver palladium), RuO₂ (ruthenium dioxide), Ta₂N (tantalum nitride), or the like in a certain shape. The protective layer 11c is made of a highly

insulating member such as glass or polyimide, and covers the resistive heating element 11b for protecting and insulating the resistive heating element 11b. The heater 11 according to the present embodiment is formed by stacking the resistive heating element 11b of Ag/Pd and the protective layer 11c of glass on the substrate 11a of alumina ceramic. The resistive heating element 11b is energized with an AC current by a power feeding unit (not illustrated) to generate heat.

10 Note that the dimensions of the substrate 11a are 270 mm in the longitudinal direction, 10 mm in the short direction, and 1.0 mm in the thickness direction. The dimension of the resistive heating element 11b is 218 mm in the longitudinal direction. In addition, the thickness (the dimension in the thickness direction) of the protective layer 11c including the resistive heating element 11b is about 60 μ m, which is much smaller than the thickness of the substrate 11a.

A front surface of the heater 11 is in contact with a back surface of the fixing film 13 via heat resistant grease 22 serving as a lubricant, and the heater 11 heats the fixing film 13. The heat resistant grease 22 is intended to reduce friction between the front surface of the heater 11 that is fixedly supported and the back surface of the fixing film 13 that rotationally moves, and reduce friction between a front surface of the heat conducting member 18 and a back surface of the heater 11, and is obtained by dispersing a fluororesin in a fluorine-based oil.

The back surface of the heater 11 is in contact with the heat conducting member 18 via the heat resistant grease 22. The heat conducting member 18 is formed of a metal plate made of a metal material, and is formed using a flat-plate aluminum material (JIS standard: A5052) having a thickness of 0.3 mm in the present embodiment. The thermal conductivity of the heat conducting member 18 is 140 W/m·K, which is larger than the thermal conductivity, 20 W/m·K, of the substrate 11a of the heater 11. Since the heat conducting member 18 having a high thermal conductivity is in contact with the back surface of the heater 11, a temperature difference generated in the longitudinal direction LD of the heater 11 can be leveled out.

In addition, the thermal expansion coefficient of the heat conducting member 18 is 24×10^{-6} [1/K], the thermal expansion coefficient of the substrate 11a of the heater 11 is 7.6×10^{-6} [1/K], and the difference therebetween is large. Meanwhile, the heat conducting member 18 and the heater 11 are held in close contact with each other. Therefore, there is a possibility that the back surface of the heater 11 may hinder a dimensional change resulting from the thermal expansion of the heat conducting member 18 due to a frictional force, and as a result, the heat conducting member 18 may be deformed or damaged. In order to avoid such a problem, the heat resistant grease 22 is applied between the back surface of the heater 11 and the front surface of the heat conducting member 18 to reduce friction therebetween. The heat resistant grease 22 is the same as the heat resistant grease 22 applied onto the front surface of the heater 11, but is not necessarily the same.

A thermistor 20 serving as a temperature detection element abuts on a back surface of the heat conducting member 18, and the thermistor 20 detects a temperature of the heater 11 via the heat conducting member 18. The thermistor 20 is connected to the control unit 32 (see FIG. 1) by a lead wire 21 to provide the detected temperature information to the control unit 32. The control unit 32 controls an AC current for energizing the resistive heating element 11b via the power feeding unit so that the heater 11 has a desired temperature. In the present embodiment, the temperature of

the thermistor 20 (or the heater 11) is controlled to be 200° C. when LTR size paper passes at a conveyance speed of 50 ppm.

Similarly to the thermistor 20, a thermoswitch (not illustrated) serving as a safety element abuts on the heater 11 via the heat conducting member 18. The thermoswitch is disposed in series with the resistive heating element 11b on an electric circuit of the power feeding unit to physically cut off the electric circuit and stop the energization of the resistive heating element 11b when the temperature of the heater 11 exceeds an operating temperature of the thermoswitch. The operating temperature of the thermoswitch in the present embodiment is 270° C. The thermoswitch is intended to prevent the fixing unit 6 from having a particularly high temperature under an irregular use condition, for example, when an unexpected sheet P such as cardboard passes through the image forming apparatus 100, and does not operate during normal use.

In addition, the longer the length in the longitudinal direction LD (hereinafter referred to as a longitudinal length) of the heat conducting member 18, the greater the effect of levelling out the temperature of the heater 11. However, if the longitudinal length of the heat conducting member 18 is too long, the temperature in the fixing nip NF decreases, reducing the fixability of the unfixed toner image T. Therefore, the longitudinal length of the heat conducting member 18 is appropriately set in accordance with the characteristics of the image forming apparatus 100 and the fixing unit 6. In the present embodiment, the longitudinal length of the heat conducting member 18 is set to 218 mm, which is the same as the length of the resistive heating element 11b. The length in the short direction SD (hereinafter referred to as a short-side length) of the heat conducting member 18 is 7 mm, and the thickness of the heat conducting member 18 is 0.3 mm.

The heater holder 12 supports the heat conducting member 18 and the heater 11. The heater holder 12 includes a heater holder front surface 12d, a second seating surface 12c disposed at a position recessed upward from the heater holder front surface 12d, and a first seating surface 12b disposed at a position recessed upward from the second seating surface 12c. As illustrated in FIGS. 3 and 4A, the heat conducting member 18 is supported by the first seating surface 12b, and the heater 11 is supported by the second seating surface 12c.

A step (distance) in the thickness direction TD between the first seating surface 12b and the second seating surface 12c is preferably equal to or smaller than the thickness of the heat conducting member 18. This is because the contact between the heater 11 and the heat conducting member 18 is not hindered. In the present embodiment, the step is 0.3 mm, which is equal to the thickness of the heat conducting member 18.

Further, the heater holder front surface 12d is in contact with the back surface of the fixing film 13 together with the front surface of the heater 11. Therefore, when the heater 11 and the heat conducting member 18 are housed in the heater holder 12, the position of the heater holder front surface 12d in the thickness direction TD is preferably substantially the same as the position of the front surface of the heater 11. Therefore, in the present embodiment, the step between the heater holder front surface 12d and the second seating surface 12c has a thickness of 1.1 mm.

Next, a positional relationship between peripheral members of the heater 11 in the longitudinal direction LD will be described with reference to FIG. 3. The heater holder 12 includes a heater positioning portion 12a against which the

heater 11 abuts in the longitudinal direction LD. The heater 11 is in contact with the second seating surface 12c of the heater holder 12 in a state where the heater 11 abuts against the heater positioning portion 12a. One end portion of the heater 11 in the longitudinal direction LD is not in contact with the back surface of the fixing film 13, and the heater 11 is held by the heater holder 12 with the one end portion thereof being held by a holding structure such as a clip with respect to the heater holder 12. The resistive heating element 11b may be connected to the power feeding unit via a connector, and the connector may be provided with a clip function for holding the heater 11 in the heater holder 12.

In FIG. 3, a right end of the heater 11 is in contact with the heater positioning portion 12a, but a left end of the heater 11 is not in contact with the heater holder 12 in the longitudinal direction LD. That is, in the longitudinal direction, a gap GH is formed between the left end of the heater 11 and the heater holder 12.

On the other hand, the heat conducting member 18 is in contact with the first seating surface 12b in the thickness direction TD. Both left and right ends of the heat conducting member 18 are not in contact with the heater holder 12 in the longitudinal direction LD. The heater 11 has protrusions 11d and 11e to be described below, and both ends of the heat conducting member 18 are spaced apart from the protrusions 11d and 11e by gaps GR and GL, respectively, in the longitudinal direction LD. In the present embodiment, in a state where the heater 11 is not heated (for example, the heater 11 is at room temperature) and the heat conducting member 18 is disposed at the center between the protrusions 11d and 11e, the lengths of the gaps GR and GL in the longitudinal direction LD are 0.5 mm.

Configuration of Protrusion

Next, the protrusions 11d and 11e will be described in detail. As illustrated in FIGS. 3 and 4B, the protrusions 11d and 11e extend in the thickness direction TD from a back surface 11m of the substrate 11a of the heater 11 toward the heater holder 12. The protrusions 11d and 11e are disposed outside the heat conducting member 18 in the longitudinal direction LD. The back surface 11m is a surface of the heater 11 provided on the side opposite to the fixing nip NF. That is, the heat conducting member 18 is disposed between the back surface 11m of the heater 11 and the first seating surface 12b of the heater holder 12.

More specifically, the heat conducting member 18 has one end 18d and the other end 18e in the longitudinal direction LD, and the protrusion 11d serving as a first protrusion faces one end 18d in the longitudinal direction LD and is disposed on the side opposite to the other end 18e with respect to one end 18d. As illustrated in FIGS. 3 and 5A, the protrusion 11d is disposed so as not to overlap the heat conducting member 18 as viewed in the short direction SD.

The protrusion 11e serving as a second protrusion faces the other end 18e in the longitudinal direction LD, and is disposed on the side opposite to one end 18d with respect to the other end 18e. As illustrated in FIGS. 3 and 5A, the protrusion 11e is disposed so as not to overlap the heat conducting member 18 as viewed in the short direction SD. The heat conducting member 18 is disposed between the protrusions 11d and 11e in the longitudinal direction LD, and a distance DS1 between the protrusions 11d and 11e is longer than a length DS2 of the heat conducting member 18.

The heat conducting member 18 expands and contracts in the longitudinal direction LD with a temperature change, and as a result, moves in the longitudinal direction LD with respect to the heater 11. However, the protrusions 11d and 11e surround the heat conducting member 18 together with

the first seating surface **12b** and the back surface **11m** of the heater **11** to restrict a movement of the heat conducting member **18** in the longitudinal direction LD. Therefore, it is not necessary to provide the heat conducting member **18** with an uneven shape for fitting the heat conducting member **18** to the heater **11** and the heater holder **12**, and the heat conducting member **18** can be configured in a simple shape, making it possible to reduce the risk of deformation and damage during thermal expansion. In addition, the protrusions **11d** and **11e** allow the heat conducting member **18** to be thermally expandable and movable in the longitudinal direction LD within the gaps **GR** and **GL**, while restricting a movement of the heat conducting member beyond the gaps **GR** and **GL**, making it possible to suppress a positional deviation of the heat conducting member **18** in the longitudinal direction LD.

In the present embodiment, the two protrusions **11d** and **11e** are provided on the back surface **11m** of the heater **11**, but the protrusions **11d** and **11e** are not limited thereto. For example, only one of the protrusions **11d** and **11e** may be provided, but it is preferable to provide the two protrusions **11d** and **11e** in terms of the functionality of the protrusions **11d** and **11e** to be described below.

FIG. 5A is a plan view illustrating the heat conducting member **18** and the protrusions **11d** and **11e** in the present embodiment. As described above, the protrusions **11d** and **11e** are disposed outside one end **18d** and the other end **18e** of the heat conducting member **18** in the longitudinal direction LD, and extend in the short direction SD. In the present embodiment, the protrusions **11d** and **11e** extend in parallel to the sheet conveyance direction **p0** and the short direction SD.

The protrusions **11d** and **11e** are not limited to the shape illustrated in FIG. 5A. For example, as illustrated in FIG. 5B, the protrusions **11d** and **11e** may extend so as to be inclined with respect to the sheet conveyance direction **p0** and the short direction SD. As a result, even when one end **18d** or the other end **18e** of the heat conducting member **18** abuts against the protrusion **11d** or **11e**, the stress generated in the heat conducting member **18** can be released in the short direction SD, suppressing deformation of the heat conducting member **18**. As illustrated in FIG. 5C, the protrusions **11d** and **11e** may be shaped to extend in the longitudinal direction LD to the ends of heater **11** in the longitudinal direction LD.

In the present embodiment, the protrusions **11d** and **11e** are formed of the same glass material as the protective layer **11c**, but the protrusions **11d** and **11e** are not limited thereto. For example, the protrusions **11d** and **11e** may be formed integrally with the substrate **11a** of the heater **11**, or the protrusions **11d** and **11e** may be formed by placing small members on the back surface **11m** of the heater **11**, and then coating the small members with the same material as the protective layer **11c**.

As illustrated in FIGS. 3 and 4B, the protrusions **11d** and **11e** are disposed at positions corresponding to the first seating surface **12b** of the heater holder **12** in the longitudinal direction LD and in the short direction SD. That is, the protrusions **11d** and **11e** face the first seating surface **12b** in the thickness direction TD.

In addition, in order to prevent the protrusions **11d** and **11e** from abutting against the first seating surface **12b**, the thickness thereof is equal to or smaller than the thickness of the heat conducting member **18**. On the other hand, in a case where the thickness of the protrusions **11d** and **11e** is significantly thin, the effect of restricting a movement of the heat conducting member **18** is weakened. Therefore, the

thickness of the protrusions **11d** and **11e** is preferably in a range of 65 to 100% of the thickness of the heat conducting member **18**. In the present embodiment, the thickness of the protrusions **11d** and **11e** is set to 0.25 mm.

5 In addition, the protrusions **11d** and **11e** may abut on end portions of the heat conducting member **18** in the longitudinal direction LD as the heat conducting member **18** thermally expands. In order for the heat conducting member **18** to stably abut on the protrusions **11d** and **11e**, the length 10 of the protrusions **11d** and **11e** in the short direction SD is preferably equal to or longer than the length of the heat conducting member **18** in the short direction SD. In the present embodiment, the length of the protrusions **11d** and **11e** in the short direction SD is set to 8 mm.

15 Effect of Protrusion

Next, an effect of the protrusions **11d** and **11e** will be described in detail with reference to FIG. 6. FIG. 6 is a cross-sectional view for explaining thermal expansion of the heater **11** and the heat conducting member **18**. FIG. 6 20 illustrates a cross section parallel to the longitudinal direction LD and the thickness direction TD.

As illustrated in FIG. 6, the right end (one end in the longitudinal direction LD) of the heater **11** abuts against the 25 positioning portion **12a** of the heater holder **12**, and the left end (the other end in the longitudinal direction LD) of the heater **11** is spaced apart from the heater holder **12** by a gap **GH**. Therefore, when the heater **11** is heated and thermally expands, the protrusion **11d** of the heater **11** facing one end **18d** of the heat conducting member **18** expands in a direction indicated by an arrow **E11R** from a position **Z11** as a starting point. Similarly, the protrusion **11e** of the heater **11** facing the other end **18e** of the heat conducting member **18** expands in a direction indicated by an arrow **E11L** from the position **Z11** as a starting point. The position **Z11** is a position in the 30 longitudinal direction LD of a contact portion where the right end of the heater **11** and the positioning portion **12a** are in contact with each other.

On the other hand, the heat conducting member **18** is disposed between the back surface **11m** of the heater **11** and the first seating surface **12b** of the heater holder **12**, but is not fixed in the longitudinal direction LD. Therefore, the heat conducting member **18** is movable with respect to the heater **11** between the protrusions **11d** and **11e**. In addition, the heat conducting member **18** thermally expands from a certain 45 point as a starting point. In FIG. 6, it is assumed that the heat conducting member **18** thermally expands from a starting point **Z18**, which is a center position of the heat conducting member **18** in the longitudinal direction LD. That is, one end **18d** of the heat conducting member **18** expands in a direction indicated by an arrow **E18R**, and the other end **18e** of the heat conducting member **18** expands in a direction indicated by an arrow **E18L**.

As described above, when the heater **11** and the heat conducting member **18** thermally expand with the operation 55 of the fixing unit **6**, the gap **GR** decreases because the protrusion **11d** moves in the left direction and one end **18d** of the heat conducting member **18** moves in the right direction in FIG. 6. On the other hand, when the heater **11** and the heat conducting member **18** thermally expand, the 60 gap **GL** decreases at a slower pace than the gap **GR** because the protrusion **11e** moves in the left direction and the other end **18e** of the heat conducting member **18** also moves in the left direction in FIG. 6.

FIG. 7 is a graph illustrating changes in the lengths of the 65 gaps **GL** and **GR** in the longitudinal direction LD when the heater **11** and the heat conducting member **18** thermally expand. The data in the graph are calculated values, and the

11

longitudinal length and the thermal conductivity of each member involved in the calculation are as described above. In the graph illustrated in FIG. 7, the horizontal axis represents temperatures of the heater 11 and the heat conducting member 18, and the vertical axis represents longitudinal lengths of the gaps GL and GR. In FIG. 7, it is assumed that the heater 11 and the heat conducting member 18 have the same temperature, and in this case, a temperature detected by the thermistor 20 (hereinafter also simply referred to as a detected temperature) is also the same as the temperatures of the heater 11 and the heat conducting member 18.

The longitudinal lengths of the gaps GL and GR are both 0.5 mm when the temperature detected by the thermistor 20 is 20° C., and decrease as the heater 11 and the heat conducting member 18 thermally expand. When one end 18d and the other end 18e of the heat conducting member 18 abut against the protrusions 11d and 11e, the longitudinal length of the gaps GL and GR become 0 mm, that is, the vertical axis in FIG. 7 becomes 0 mm. The horizontal axis indicates a temperature at that point when one end 18d and the other end 18e of the heat conducting member 18 abut against the protrusions 11d and 11e (hereinafter referred to as an abutment temperature). That is, the abutment temperature is a temperature detected by the thermistor 20 when the distance DS1 between the protrusions 11d and 11e illustrated in FIG. 3 becomes equal to the length DS2 of the heat conducting member 18.

In FIG. 7, data about the gap GR is indicated by ●. The longitudinal length of the gap GR becomes 0 mm when the detected temperature is 196° C., and at this time, one end 18d of the heat conducting member 18 abuts against the protrusion 11d. In FIG. 7, data about the gap GL is indicated by ■. The longitudinal length of the gap GL does not become 0 mm even when the detected temperature is 350° C., and the other end 18e of the heat conducting member 18 and the protrusion 11e do not abut against each other unless the heater 11 is heated to a temperature higher than that on the gap GR side.

Here, as described above, the starting point Z18 of expansion of the heat conducting member 18 is not a structurally strongly fixed point, but a starting point of temporary expansion of the heat conducting member 18 that can relatively freely move in the longitudinal direction LD. Therefore, after one end 18d of the heat conducting member 18 abuts against the protrusion 11d at the detected temperature of 196° C., when the temperature of the heater 11 further rises, the heat conducting member 18 thermally expands toward the other end 18e in the longitudinal direction LD from the protrusion 11d as a starting point. Therefore, the longitudinal length of gap GL decreases more rapidly when the detected temperature is equal to or higher than 196° C. than when the detected temperature is lower than 196° C. (the data at that time is indicated by u in FIG. 7).

If the detected temperature rises up to 300° C., both the gap GR and the gap GL become 0 mm, and both one end 18d and the other end 18e of the heat conducting member 18 abut against the protrusions 11d and 11e. Further, when the detected temperature exceeds 300° C. and the temperature of the heater 11 rises, one end 18d and the other end 18e of the heat conducting member 18 increase their pressing force to the protrusions 11d and 11e with the thermal expansion of the heat conducting member 18, and the heat conducting member 18 may be deformed or damaged.

On the other hand, as described above, in the present embodiment, the control unit 32 controls the heater 11 so that the temperature detected by the thermistor 20 becomes 200° C., and the temperatures of the heater 11 and the heat

12

conducting member 18 including temperature variations do not exceed 270° C., which is an operating temperature of the thermoswitch. Therefore, both the gaps GR and GL do not become 0 mm, and one end 18d and the other end 18e of the heat conducting member 18 are not excessively pressed against the protrusions 11d and 11e, such that the heat conducting member 18 is not deformed or damaged. In other words, when the sheet P is conveyed by the fixing nip NF, the protrusions 11d and 11e do not simultaneously abut on the heat conducting member 18. Therefore, if the protrusions 11d and 11e and the heat conducting member 18 are arranged in the longitudinal direction LD so that the detected temperature is 300° C. and the gaps GR and GL are 0 mm, deformation or damage to the heat conducting member 18 can be reliably avoided.

Further, in the fixing unit 6 according to the present embodiment, the longitudinal lengths of the gaps GR and GL are both set to 0.5 mm when the temperature detected by the thermistor 20 is 20° C. as described above. By increasing the longitudinal lengths of the gaps GR and GL, the abutment temperature can be increased. However, in this case, since the movable range of the heat conducting member 18 in the longitudinal direction LD is increased, the heat conducting member 18 may be significantly closer to the protrusion 11d or the protrusion 11e in the longitudinal direction LD.

For example, in a state where the heat conducting member 18 is close to the protrusion 11d, one end 18d of the heat conducting member 18 moves to the outside of the resistive heating element 11b in the longitudinal direction LD, and the heat conducting member 18 levels out the temperature up to a range where the resistive heating element 11b does not exist. As a result, the temperature in the fixing nip NF decreases, reducing the fixability of the toner onto the sheet P. In addition, since a partial portion (a left end portion) of the resistive heating element 11b is located outside the other end 18e of the heat conducting member 18 in the longitudinal direction LD, the temperature in the fixing nip NF increases in that range, excessively heating the left end portion of the resistive heating element 11b with respect to the sheet P and the toner.

Meanwhile, the accuracy in image writing position of the image forming apparatus such as a printer or a copier is generally ± 2 mm. This variation in accuracy is caused by a variation in the conveyed position of the sheet P in the image forming apparatus 100. In the fixing unit 6, the arrangement of each member in the longitudinal direction LD is designed so that stable fixing performance can be obtained even if such a variation in the conveyed position of the sheet P occurs. On the other hand, a positional deviation of the heat conducting member 18 in the longitudinal direction LD caused by the longitudinal lengths of the gaps GR and GL is ± 0.5 mm, which is sufficiently smaller than the variation in the conveyed position of the sheet P. Therefore, even if the position of the heat conducting member 18 deviates in the longitudinal direction LD within the range of the gaps GR and GL set to 0.5 mm, the fixability of the toner onto the sheet P is not affected.

As described above, in the fixing unit 6 according to the present embodiment, the heat conducting member 18 is disposed on the back surface 11m of the heater 11, and the protrusions 11d and 11e are provided on the back surface 11m of the heater 11. Since the protrusions 11d and 11e face one end 18d and the other end 18e of the heat conducting member 18 with gaps GR and GL of appropriate longitudinal lengths therebetween, a movement of the heat conducting member 18 in the longitudinal direction LD can be

restricted between the protrusions **11d** and **11e**. Then, since the heat conducting member **18** is not processed into a shape that fits the heater **11**, deformation or damage caused due to residual stress resulting from the processing does not occur. With such a configuration, stable fixing performance can be obtained without causing deformation or damage to the heat conducting member **18**, and image defects can be reduced.

Next, in each case where the longitudinal length of the gaps GR and GL when the detected temperature is 20°C. is changed, the temperature of the heater **11** or the detected temperature at which the gaps GR and GL become 0 mm is shown in Table 1 below.

TABLE 1

	Longitudinal length of gaps GR and GL at 20°C.	Temperature when gap GR is 0 mm	Temperature when gap GL is 0 mm
Example 1	0.5 mm	196°C.	300°C.
Comparative example 1	0.25 mm	108°C.	160°C.
Comparative example 2	0.8 mm	>300°C.	>300°C.

The temperature values in Table 1 are calculated values as described above. In the present embodiment (Example 1), the longitudinal length of the gaps GR and GL when the detected temperature is 20°C. is 0.5 mm, and the detected temperature at which the gap GR is 0 mm, that is, one end **18d** of the heat conducting member **18** abuts against the protrusion **11d**, is 196°C. In addition, the detected temperature at which the gap GL is 0 mm, that is, the other end **18e** of the heat conducting member **18** abuts against the protrusion **11e**, is 300°C.

Further, the longitudinal length of the gaps GR and GL when the detected temperature is 20°C. is changed to 0.25

against the protrusions **11d** and **11e**, respectively, at the time of the image forming job. This may cause deformation or damage to the heat conducting member **18**, which is not preferable.

In Comparative Example 2, the detected temperature at which the gap GR is 0 mm, that is, one end **18d** of the heat conducting member **18** abuts against the protrusion **11d**, is higher than 300°C. In addition, the detected temperature at which the gap GL is 0 mm, that is, the other end **18e** of the heat conducting member **18** abuts against the protrusion **11e**, is also higher than 300°C. Therefore, there is no possibility that one end **18d** and the other end **18e** of the heat conducting member **18** abut against the protrusions **11d** and **11e** at the time of an image forming job. On the other hand, the movable range of the heat conducting member **18** in the longitudinal direction LD is 0.3 mm larger on each of the gap GR side and the gap GL side than that in the present embodiment. This may cause a positional deviation of the heat conducting member **18** in the longitudinal direction LD, thereby making the temperature of the fixing nip NF unstable, and reducing the fixability of the toner.

Therefore, the longitudinal length of the gaps GR and GL is preferably as small as possible within a range of the length secured such that the heat conducting member **18** does not abut against both the protrusions **11d** and **11e** even when the heat conducting member **18** thermally expands during an image forming job. In Table 1 described above, the present embodiment (Example 1) is more preferable than Comparative Examples 1 and 2.

Next, it was confirmed whether the above-described effect can be similarly obtained in a case where the starting point **Z18** of expansion of the heat conducting member **18** is displaced in the longitudinal direction LD as shown in Table 2 below.

TABLE 2

	Longitudinal length of gaps GR and GL at 20°C.	Displacement of starting point Z18 of expansion from longitudinal center	Temperature when gap GR is 0 mm	Temperature when gap GL is 0 mm
Example 1	0.5 mm	0 mm	196°C.	300°C.
Example 1-1	0.5 mm	30 mm leftward	160°C.	300°C.
Example 1-2	0.5 mm	60 mm leftward	137°C.	300°C.
Example 1-3	0.5 mm	30 mm rightward	255°C.	300°C.
Example 1-4	0.5 mm	60 mm rightward	300°C.	252°C.

mm in Comparative Example 1, and the longitudinal length of the gaps GR and GL when the detected temperature is 20°C. is changed to 0.8 mm in Comparative Example 2. In Comparative Example 1, each of the protrusions **11d** and **11e** according to the present embodiment is moved inward by 0.25 mm in the longitudinal direction LD. In Comparative Example 2, each of the protrusions **11d** and **11e** according to the present embodiment is moved outward by 0.3 mm in the longitudinal direction LD.

In Comparative Example 1, the detected temperature at which the gap GR is 0 mm, that is, one end **18d** of the heat conducting member **18** abuts against the protrusion **11d**, is 108°C. In addition, the detected temperature at which the gap GL is 0 mm, that is, the other end **18e** of the heat conducting member **18** abuts against the protrusion **11e**, is 160°C. In the fixing unit **6** according to the present embodiment, since the target temperature of the heater **11** is set to 200°C. during an image forming job, one end **18d** and the other end **18e** of the heat conducting member **18** abut

In Table 2, Example 1 was carried out under the above-described condition according to the present embodiment described above, in which the starting point **Z18** of expansion of the heat conducting member **18** coincides with the center position of the heat conducting member **18** in the longitudinal direction LD. On the other hand, each of Examples 1-1 to 1-4 was carried out under a condition in which the starting point **Z18** is displaced leftward or rightward by 30 mm or 60 mm in the longitudinal direction LD of FIG. 3 from the center position of the heat conducting member **18** in the longitudinal direction LD. The temperatures at which the gaps GR and GL become 0 mm under each condition are calculated values, similarly to those in Table 1. This confirmation was performed because the starting point **Z18** of expansion is easily displaced in the longitudinal direction LD due to minute load unevenness in the fixing nip **6** when the sheet **P** is conveyed to the fixing unit **6**. Therefore, in Table 2, calculations were performed assuming significantly large displacement of up to 60 mm.

Under the conditions in Examples 1-1 to 1-3, the detected temperature when the longitudinal length of the gap GL becomes 0 mm is 300° C. In the fixing unit 6, since the target temperature of the heater 11 is 200° C. and the operating temperature of the thermoswitch is 270° C., both one end 18d and the other end 18e of the heat conducting member 18 do not abut against the protrusions 11d and 11e at the time when the image forming apparatus 100 is actually used.

Under the condition in Example 1-4, the other end 18e of the heat conducting member 18 abuts against the protrusion 11e before one end 18d of the heat conducting member 18 abuts against the protrusion 11d, but the abutment temperature at which both one end 18d and the other end 18e of the heat conducting member 18 abut against the protrusions 11d and 11e is 300° C. Therefore, at the time when the image forming apparatus 100 is actually used, both one end 18d and the other end 18e of the heat conducting member 18 do not abut against the protrusions 11d and 11e, as is the case with the conditions in Examples 1-1 to 1-3.

Therefore, by appropriately setting the longitudinal length of the gaps GR and GL, deformation or damage to the heat conducting member 18 can be reduced even under a condition where the starting point Z18 of expansion of the heat conducting member 18 is biased to the left and right in the longitudinal direction LD.

First Modification of First Embodiment

Next, a first modification of the first embodiment will be described. In the first modification of the first embodiment, the longitudinal length of the heat conducting member 18 is shorter than that in the first embodiment. Therefore, a configuration thereof similar to that of the first embodiment will not be illustrated or will be described with the same reference signs being given in the drawings.

In the first embodiment, the longitudinal length of the heat conducting member 18 is set to be the same as that of the resistive heating element 11b, but the longitudinal length of the heat conducting member 18 is not limited thereto. FIG. 8 is a cross-sectional view illustrating a cross section parallel to the longitudinal direction LD of a peripheral configuration of the heater 11 according to the first modification of the first embodiment. As illustrated in FIG. 8, a heat conducting member 118 according to the present first modification is shorter than the resistive heating element 11b in the longitudinal direction LD, and is disposed closer to the left side of the heater 11.

In the present first modification, the sheet P is conveyed with one end thereof in a width direction parallel to the longitudinal direction LD being set to a reference position ZP. That is, the sheet P is conveyed in a state where one side (one end in the width direction) of the sheet P coincides with the reference position ZP regardless of the size of the sheet. For example, the sheet P is conveyed while one side thereof is in rubbing contact with a reference surface provided in a conveyance guide (not illustrated), so that the sheet P is conveyed along the reference position ZP on a one-side basis.

In such a configuration, the sheet non-passage range in the fixing nip NF when a sheet P having a narrow width is conveyed is only the left side in FIG. 8, and the heat conducting member 118 is disposed to correspond to such a sheet non-passage range, thereby making it possible to configure the heat conducting member 118 to be short. By shortening the longitudinal length of the heat conducting member 118, a change in length of the heat conducting member 118 during thermal expansion can be reduced, so

that the gaps GR and GL can be set to be narrower than those in the first embodiment described above.

In addition, in the configuration as in the present first modification, the starting point of expansion of the heat conducting member 118 is often one end 118d of the heat conducting member 118. This is because the position of the starting point is affected by the pressure distribution and the temperature distribution in the longitudinal direction LD of the fixing nip NF. For example, in a case where one end 118d of the heat conducting member 118 is the starting point of expansion, the heat conducting member 118 thermally expands only toward the other end 118e. For this reason, only the protrusion 11e may be provided on the heater 11 without providing the protrusion 11d.

In the heater holder 12, it is also preferable that the length of the first seating surface 12b corresponding to the heat conducting member 118 is shorter than that in the first embodiment, and the length of the second seating surface 12c is longer than that in the first embodiment. In FIG. 8, the heater 11 may be bonded to a region CP of the second seating surface 12c via a heat-resistant adhesive.

Second Modification of First Embodiment

Next, a second modification of the first embodiment will be described. In the second modification of the first embodiment, protrusions 11f and 11g are provided in addition to the protrusions 11d and 11e on the back surface 11m of the heater 11. Therefore, a configuration thereof similar to that of the first embodiment will not be illustrated or will be described with the same reference signs being given in the drawings.

As illustrated in FIG. 9A, the protrusion 11f serving as a third protrusion disposed on one side in the short direction SD of the heat conducting member 18 and the protrusion 11g serving as a fourth protrusion disposed on the other side in the short direction SD of the heat conducting member 18 extend from the back surface 11m of the heater 11. In other words, the heat conducting member 18 is disposed with gaps between the protrusions 11f and 11g in the short direction SD. In addition, the protrusions 11f and 11g are disposed on opposite sides in the short direction SD with the heat conducting member 18 interposed therebetween while facing the heat conducting member 18, and are disposed so as not to overlap the heat conducting member 18 when viewed in the longitudinal direction LD.

There has been known a configuration in which a pressure of a load applied to the fixing film unit 19 is reduced in order for a user to easily remove a jammed sheet when the sheet P is stuck in the fixing nip NF, that is, when a so-called jam occurs. In such a pressure-reduced state, in a case where the jammed sheet is pulled out and removed in a direction or angle different from the normal sheet conveyance direction p0 of the sheet P, there is a possibility that the heat conducting member 18 is deviated in the short direction SD with respect to the heater 11. This is because the heat conducting member 18 is not fixed to the first seating surface 12b of the heater holder 12 or the back surface 11m of the heater 11. The protrusions 11f and 11g according to the present modification have an effect of preventing such a deviation of the heat conducting member 18 in the short direction SD.

A change of the heat conducting member 18 in the short-side length during thermal expansion is not as large as that in the longitudinal direction LD. Therefore, gaps between the heat conducting member 18 and the protrusions 11f and 11g in the short direction SD can be set to be

narrower than the gaps GR and GL. In addition, in order to prevent the protrusions 11f and 11g from abutting against the first seating surface 12b, the thickness thereof is equal to or smaller than the thickness of the heat conducting member 18. On the other hand, in a case where the thickness of the protrusions 11f and 11g is significantly thin, the effect of restricting a movement of the heat conducting member 18 is weakened. Therefore, the thickness of the protrusions 11f and 11g is preferably in a range of 65 to 100% of the thickness of the heat conducting member 18. In the present modification, the thickness of the protrusions 11f and 11g is set to 0.25 mm, which is the same as the thickness of the protrusions 11d and 11e.

If the protrusions 11f and 11g and the protrusions 11d and 11e are structurally connected to each other, this affects displacement of the protrusions 11d and 11e when the heater 11 thermally expands. Therefore, it is preferable that the protrusions 11f and 11g and the protrusions 11d and 11e are not connected to each other.

As illustrated in FIG. 9B, the protrusions 11f and 11g may be discontinuous in the longitudinal direction LD as long as the effect of restricting a movement of the heat conducting member 18 is not lost.

Furthermore, as illustrated in FIG. 9C, in a case where the protrusions 11f and 11g are provided only at the longitudinal end portions, this hardly affects displacement of the protrusions 11d and 11e. Therefore, the protrusions 11f and 11g and the protrusions 11d and 11e may be connected to each other.

As described above, by providing the protrusions 11f and 11g outside the heat conducting member 18 in the short direction SD, it is possible to reduce a deviation of the heat conducting member 18 in the short direction SD.

Second Embodiment

Next, a second embodiment of the present invention will be described. In the second embodiment, a heater 110 is used instead of the heater 11 according to the first embodiment. Therefore, a configuration thereof similar to that of the first embodiment will not be illustrated or will be described with the same reference signs being given in the drawings.

FIG. 10A is a front view illustrating a front surface of the heater 110 according to the present embodiment, and FIG. 10B is a front view illustrating a back surface 110m of the heater 110. As illustrated in FIG. 10A, similarly to the heater 11 according to the first embodiment, the heater 110 includes a substrate 11a, a resistive heating element 11b, and a protective layer (not illustrated) on the front surface thereof. The resistive heating element 11b is energized with an AC current through a contact 11h by a power feeding unit (not illustrated) to generate heat.

As illustrated in FIG. 10B, on the back surface of heater 110, a thermistor 200 serving as a temperature detection unit that detects a temperature of the heater 110 and a printed wire 201 for controlling the thermistor are directly provided on the substrate 11a in an adhesive and printed manner. The printed wire 201 serving as a wiring pattern has a connecting portion 201a to provide detected temperature information to the control unit 32 (see FIG. 1) via a lead wire (not illustrated) electrically connected to the connecting portion 201a. Note that the thermistor 200 according to the present embodiment can accurately measure a temperature of the heater 110 without using a useless member, because a chip thermistor that can be mounted on the substrate 11a is used therefor. At the same time, the space can be saved as

compared with that in the configuration of the thermistor 200 (see FIG. 3) according to the first embodiment.

Peripheral Configuration of Heater

Next, a peripheral configuration of the heater 110 will be described. FIG. 11 is a cross-sectional view when the heater 110 is disposed in a fixing unit 206. In the present embodiment, the fixing film unit 190 is used instead of the fixing film unit 19 according to the first embodiment. The fixing film unit 190 includes a fixing film 13 and a heater 110 disposed in the fixing film 13. Further, the fixing film unit 190 includes a heater holder 12 supporting the heater 110, and an insulating layer 24 and a heat conducting member 180 disposed between the back surface 110m of the heater 110 and the heater holder 12. The insulating layer 24 is provided integrally with the back surface 110m of the heater 110 so as to cover at least a part of the thermistor 200 and the printed wire 201, and is disposed between the back surface 110m and the heat conducting member 180. In the present embodiment, the insulating layer 24 is provided integrally with the back surface 110m of the heater 110, but the insulating layer 24 is not limited thereto. For example, the insulating layer 24 may be provided integrally with the heat conducting member 180. The basic operation of the fixing unit 206 and the effect of the heat conducting member 180 are the same as those of the fixing unit 6 described in the first embodiment.

In many cases, a graphite sheet or a metal plate of aluminum, iron, copper, or the like having high thermal conductivity is used as the heat conducting member 180. Thus, if the heat conducting member is directly disposed on the thermistor 200 or the printed wire 201, a short circuit or a leakage may occur. In order to prevent a short circuit or a leakage, in the present embodiment, the insulating layer 24 is provided on the heater 110 as described above, such that the heat conducting member 180 does not directly contact the thermistor 200 and the printed wire 201. The heat conducting member 180 may be made of a material other than the materials described above as long as the heat conducting member 180 has a thermal conductivity of 80 [W/mK] or more. Furthermore, for example, glass, polyimide, or the like is used for the insulating layer 24.

Peripheral Configurations and Operations of Thermistor and Printed Wire

Next, peripheral configurations and operations of the thermistor 200 and the printed wire 201 will be described with reference to FIGS. 11, 12, and 13. FIG. 12 is a front view illustrating the back surface 110m of the heater 110 in a state where the heat conducting member 180 is disposed on the heater 110. FIG. 13 is a cross-sectional view illustrating a cross section taken along line 13A-13A of FIG. 12. In FIG. 13, the heater 110 and the heat conducting member 180 are disposed on the heater holder 12.

The lead wire 21 is bonded to the connecting portion 201a on the printed wire 201 by means of welding, pressure contact, brazing, ultrasonic bonding, or the like, and the lead wire 21 is connected to the control unit 32 (see FIG. 1). The control unit 32 energizes the resistive heating element 11b with an AC current so that the heater 110 has a desired temperature.

The length (longitudinal length) and the width (short-side length) of the heat conducting member 180 are set to be the same as those of the heat conducting member 18 according to the first embodiment. In addition, a hole 180a is provided around the lead wire 21 and the connecting portion 201a so as to secure an insulation distance of the heat conducting member 180 with respect to the lead wire 21 and the connecting portion 201a. That is, the insulating layer 24 and

the heat conducting member 180 have respective holes 24a and 180a as openings through which the lead wire 21 as a conductive wire is wired. The heater holder 12 also has a hole 12e that is continuous with the hole 180a, so that the lead wire 21 can be wired to an upper portion of the heater holder 12.

Note that the size of the hole 180a of the heat conducting member 180 is preferably as small as possible if an insulation distance is secure, in order to enhance as much as possible the temperature leveling-out effect between a sheet passing portion, which is a region through which the sheet P passes, and a sheet non-passing portion, which is a region through which the sheet P does not pass, of the heater 110. In the present embodiment, the insulating layer 24 is provided in the same range as the heat conducting member 180 in the longitudinal direction LD and in the short direction SD, such that there is no space between the heater 110 and the heat conducting member 180. However, in a range where the thermistor 200 and the printed wire 201 are not present, the insulating layer 24 may not be provided because there is no risk of short circuit or leakage. In this case, it is preferable to devise a shape to increase the thickness of the heat conducting member 180 or the like, so that there is no space between the heater 110 and the heat conducting member 180.

As described above, in the present embodiment, by using the heater 110 with the thermistor 200 being directly disposed on the substrate 11a of the heater 110, it is possible to save space as compared with the configuration of the thermistor according to the first embodiment, and it is also possible to accurately measure a temperature of the heater 110. In addition, by providing the insulating layer 24 and the heat conducting member 180 between the heater 110 and the heater holder 12, it is possible to level out the temperature difference in the sheet non-passage area while suppressing a leakage and a short circuit.

First Modification of Second Embodiment

Next, a first modification of the second embodiment will be described. In the first modification of the second embodiment, a hole 180b for the thermistor 200 is formed in addition to the hole 180a in the heat conducting member 180 according to the second embodiment. Therefore, a configuration thereof similar to that of the second embodiment will not be illustrated or will be described with the same reference signs being given in the drawings.

FIG. 14 is a front view illustrating the back surface 110m of the heater 110 in a state where the heat conducting member 180 is disposed on the heater 110. FIG. 15 is a cross-sectional view illustrating a cross section taken along line 15A-15A of FIG. 14. In FIG. 15, the heater 110 and the heat conducting member 180 are disposed on the heater holder 12.

In the heat conducting member 180 according to the present modification, a hole 180b is formed around the thermistor 200 in addition to the hole 180a around the connecting portion 201a described in the second embodiment. That is, the heat conducting member 180 has a hole 180b as an opening at a position corresponding to the thermistor 200. This is to secure an insulation distance between the thermistor 200 and the heat conducting member 180. As a result, there is no need to provide the insulating layer 240 on the thermistor 200, making it possible to reduce the thickness of the insulating layer 240 as compared with

that in the second embodiment. In other words, the insulating layer 240 has an opening 240a at a position corresponding to the thermistor 200.

In the present modification, the insulating layer 240 is not provided around the thermistor 200 in the same range as the hole 180b, but it does not matter whether the range in which the insulating layer 240 is not provided around the thermistor 200 is large or small as long as the insulation distance is not affected. In addition, since the insulating layer 240 can be thinner than that in the second embodiment, the insulating layer 240 may be in the form of a sheet mainly made of polyimide, perfluoroalkoxy fluorine resin (PFA), polytetrafluoroethylene resin (PTFE), tetrafluoroethylene-hexafluoropropylene resin (FEP), or the like.

Furthermore, in the second embodiment, the insulating layer 24 is integrally formed with the heater 110. However, in the present modification, the insulating layer 24 may be integrally formed with the heat conducting member 180, or the insulating layer 24 may be simply sandwiched between the heat conducting member 180 and the heater 110. In the present modification, similarly to the second embodiment, the insulating layer 240 is provided in the same range as the heat conducting member 18, other than the periphery of the thermistor 200, but the insulating layer 240 is not limited thereto. For example, in a range where the printed wire 201 is not present, the insulating layer 240 may not be provided because there is no risk of short circuit or leakage.

Second Modification of Second Embodiment

Next, a second modification of the second embodiment will be described. In the second modification of the second embodiment, a throttle-like shape is added to the heater holder 12 and the heat conducting member 180 according to the second embodiment by retracting from the thermistor 200. Therefore, a configuration thereof similar to that of the second embodiment will not be illustrated or will be described with the same reference signs being given in the drawings.

FIG. 16 is a front view illustrating the back surface 110m of the heater 110 in a state where the heat conducting member 180 is disposed on the heater 110. FIG. 17 is a cross-sectional view illustrating a cross section taken along line 17A-17A of FIG. 16. In FIG. 17, the heater 110 and the heat conducting member 180 are disposed on the heater holder 12.

In the heat conducting member 180 according to the present modification, a throttle-like shape 180c is formed around the thermistor 200 in addition to the hole 180a around the connecting portion 201a described in the second embodiment. That is, the heat conducting member 180 has a throttle-like shape 180c serving as a recess recessed in a direction away from the thermistor 200 at a position corresponding to the thermistor 200. This is to secure an insulation distance between the thermistor 200 and the heat conducting member 180. As a result, there is no need to provide the insulating layer 240 on the thermistor 200, making it possible to reduce the thickness of the insulating layer 240 as compared with that in the second embodiment.

Furthermore, since the hole 180b is not provided in the heat conducting member 180 as in the first modification of the second embodiment, it is possible to suppress blocking of heat transfer on the heat conducting member 180, and it is possible to further enhance the temperature leveling-out effect between the sheet passing portion and the sheet non-passing portion as compared with that in the first modification of the second embodiment. In the present

modification, the insulating layer 240 is not provided around the thermistor 200 in the same range as the throttle-like shape 180c, but it does not matter whether the range in which the insulating layer 240 is not provided around the thermistor 200 is large or small as long as the insulation distance is not affected. In addition, as in the first modification, the insulating layer 240 may be in the form of a sheet.

Needless to say, in the configuration described in the second embodiment (including the first and second modifications thereof) as well, a deviation of the heat conducting member 18 in the longitudinal direction LD can be reduced by providing the protrusions 11d and 11e described in the first embodiment on the back surface of the heater.

Third Embodiment

Next, a third embodiment of the present invention will be described. In the third embodiment, a hole for allowing the lead wire 21 to pass through the heater holder 12 is formed without performing processing for forming a hole or a throttle in the insulating layer of the heater 110 or the heat conducting member 180 as in the second embodiment. Therefore, a configuration thereof similar to that of the second embodiment will not be illustrated or will be described with the same reference signs being given in the drawings.

FIG. 18A is a front view illustrating a front surface of the heater 110 according to the present embodiment, and FIG. 18B is a front view illustrating a back surface of the heater 110. The front surface of the heater 110 has the same configuration as that of FIG. 10A described in the second embodiment.

As illustrated in FIG. 18B, on the back surface of heater 110, a thermistor 200 that detects a temperature of the heater 110 and a printed wire 201 for controlling the thermistor are directly provided on the substrate 11a in an adhesive and printed manner. The lead wire 21 (see FIGS. 19 and 20) is bonded to the connecting portion 201a on the printed wire 201 by means of welding, pressure contact, brazing, ultrasonic bonding, or the like, and the lead wire 21 is connected to the control unit 32 (see FIG. 1).

In the present embodiment, the connecting portion 201a of the printed wire 201 is provided outside the resistive heating element 11b provided on the front surface of the heater 110 in the longitudinal direction LD. That is, the connecting portion 201a and the resistive heating element 11b are disposed so as not to overlap each other in the thickness direction TD (see FIG. 20). In the present embodiment, as illustrated in FIGS. 18A and 18B, the contact 11h is provided on one end side (a right side) in the longitudinal direction LD of the heater 110, and the connecting portion 201a is provided on the other end side (a left side) in the longitudinal direction LD of the heater 110. That is, the connecting portion 201a is disposed on the side opposite to the contact 11h across the heat conducting member 18 in the longitudinal direction LD. As a result, a wire connected to the contact 11h and a wire connected to the connecting portion 201a do not interfere with each other. The contact 11h and the connecting portion 201a may be collectively disposed on one end side or the other end side of the heater 110 as long as a wiring space can be secured.

As illustrated in FIGS. 19 and 20, the lead wire 21 connected to the connecting portion 201a of the printed wire 201 is connected to the control unit 32 (see FIG. 1) through a hole 12h provided in the first seating surface 12b of the heater holder 12. Similarly to the connecting portion 201a, the hole 12h is disposed outside the resistive heating element

11b and the heat conducting member 18 in the longitudinal direction LD. The hole 12h is disposed on the same side as the connecting portion 201a with respect to the heat conducting member 18 in the longitudinal direction LD.

5 An insulating layer 24 is disposed between the heat conducting member 18 and the back surface 11m of the heater 110, and the insulating layer 24 is integrally provided on the back surface of the heater 110 so as to cover the thermistor 200 and the printed wire 201. As a result, the thermistor 200 and the printed wire 201 are prevented from directly abutting on the heat conducting member 18 and causing a short circuit, a leakage, or the like. In the present embodiment, the connecting portion 201a of the printed wire 201 is disposed outside the insulating layer 24 and the heat conducting member 18 in the longitudinal direction LD.

10 In the present embodiment, the insulating layer 24 is provided in the same range as the heat conducting member 18 in the longitudinal direction LD and in the short direction SD, such that there is no space between the heater 110 and the heat conducting member 18. However, in a range where the thermistor 200 and the printed wire 201 are not present, the insulating layer 24 may not be provided because there is no risk of short circuit or leakage. In this case, it is preferable to devise a shape to increase the thickness of the heat conducting member 18 or the like, so that there is no space between the heater 110 and the heat conducting member 18.

15 As described above, in the present embodiment, the connecting portion 201a of the printed wire 201, the lead wire 21 connected to the connecting portion 201a, and the hole 12h of the heater holder 12 are disposed outside the resistive heating element 11b, the insulating layer 24, and the heat conducting member 18 in the longitudinal direction LD. As a result, there is no need to perform processing for forming a hole or the like for allowing the lead wire 21 to pass through the heat conducting member 18 or the first seating surface 12b of the heater holder 12 in a heat generating region of the resistive heating element 11b, making it possible to improve the temperature leveling-out effect of the heat conducting member 18 in the heat generating region of the heater 110. In addition, since the heat conducting member 18 and the heater holder 12 do not need to be processed, the cost can be reduced, and the possibility of deformation or damage occurring when the heat conducting member 18 thermally expands due to the influence of residual stress caused by the processing can be reduced.

First Modification of Third Embodiment

20 Next, a first modification of the third embodiment of the present invention will be described. In the first modification of the third embodiment, a plurality of thermistors and printed wires are provided on the back surface of the heater 110. Therefore, a configuration thereof similar to that of the third embodiment will not be illustrated or will be described 25 with the same reference signs being given in the drawings.

25 FIG. 21 is a front view illustrating the back surface 110m of the heater 110 according to the present modification, and FIG. 22 is a front view illustrating the back surface 110m of the heater 110 in a state where the heat conducting member 18 is disposed on the heater 110. As illustrated in FIG. 21, in the present modification, a plurality of (three in the present modification) thermistors 200, 200L, and 200R are provided on the back surface 110m of the heater 110.

30 The fixing unit 6 (see FIG. 2) according to the present modification is a so-called center-based fixing unit in which the conveyance reference position of the sheet P is the center of the fixing unit 6 in the longitudinal direction LD. The

thermistor 200 is disposed at a central portion in the longitudinal direction LD of the fixing unit 6, that is, at a central portion in the longitudinal direction LD of the fixing nip NF, so as to overlap a region through which the sheet P passes, regardless of the size of the sheet P.

On the other hand, the thermistors 200L and 200R are disposed at positions away by 99 mm from the conveyance reference position of the sheet P, that is, the center of the fixing nip NF in the longitudinal direction LD, on the left and right sides, respectively, so as to overlap the sheet non-passage range when A5 paper is printed.

The control unit 32 (see FIG. 1) energizes the resistive heating element 11b based on a temperature detected by the thermistor 200 so that the heater 110 has a desired temperature. The thermistors 200L and 200R have a role of monitoring a temperature of the sheet non-passage region when narrow paper such as A5 paper is printed. When the temperature of any of the thermistors 200L and 200R becomes higher than or equal to a predetermined temperature, the control unit 32 performs control to stop the printing or to increase an interval at which the sheets P are fed.

As in the example illustrated in FIG. 20, the heat conducting member 18 has the same longitudinal length as the resistive heating element 11b. The connecting portion 201a of the printed wire 201 corresponding to each of the thermistors 200, 200L, and 200R is disposed outside the resistive heating element 11b and the heat conducting member 18 in the longitudinal direction LD. Then, the lead wire 21 connected to each connecting portion 201a is connected to the control unit 32 (see FIG. 1) through the hole 12h provided in the first seating surface 12b of the heater holder 12, similarly to that in the third embodiment.

As described above, in the present modification, also in the configuration in which the plurality of thermistors 200, 200L, and 200R are disposed, the connecting portion 201a, the lead wire 21, and the hole 12h of the heater holder 12 are disposed outside the resistive heating element 11b and the heat conducting member 18 in the longitudinal direction LD. As a result, there is no need to perform processing for forming a hole or the like for allowing the lead wire 21 to pass through the heat conducting member 18 or the first seating surface 12b of the heater holder 12 in a heat generating region of the resistive heating element 11b, making it possible to improve the temperature leveling-out effect of the heat conducting member 18 in the heat generating region of the heater 110. This effect is greater in the configuration in which a plurality of thermistors and a plurality of lead wires for the respective thermistors are provided.

In the present modification, all the connecting portions 201a corresponding to the thermistors 200, 200L, and 200R, respectively, are disposed on the other end side (the left side) in the longitudinal direction LD of the heater 110, but the connecting portions 201a are not limited thereto. For example, the plurality of connecting portions 201a may be arranged in a distributed manner on one end side (the right side) and the other end side (the left side) in the longitudinal direction LD of the heater 110.

Second Modification of Third Embodiment

Next, a second modification of the third embodiment of the present invention will be described. In the second modification of the third embodiment, the longitudinal length of the heat conducting member 18 is shorter than that in the first modification of the third embodiment. Therefore, a configuration thereof similar to that of the first embodiment of the third embodiment will not be illustrated or will be described with the same reference signs being given in the drawings.

In the present second modification, regardless of the size of the sheet, the sheet P is conveyed in a state where one side (one end in the width direction) of the sheet P coincides with the reference position ZP, that is, conveyed on a so-called one-side basis. FIG. 23 is a front view illustrating the back surface 110m of the heater 110 according to the present modification, and FIG. 24 is a front view illustrating the back surface 110m of the heater 110 in a state where the heat conducting member 18 and the insulating layer 24 are disposed on the heater 110. FIG. 25 is a side view illustrating a peripheral configuration of the heater 110. FIG. 25 is a cross-sectional view illustrating a cross section perpendicular to the short direction SD, that is, a cross section extending in the longitudinal direction LD and the thickness direction TD.

In the present modification, one end (one side) of the sheet P in the width direction parallel to the longitudinal direction LD is conveyed with reference to the reference position ZP illustrated in FIG. 25. That is, the sheet P is conveyed in a state where one side (one end in the width direction) of the sheet P coincides with the reference position ZP regardless of the size of the sheet. For example, the sheet P is conveyed while one side thereof is in rubbing contact with a reference surface provided in a conveyance guide (not illustrated), so that the sheet P is conveyed along the reference position ZP on a one-side basis.

As illustrated in FIG. 23, in the present modification, a plurality of (two in the present modification) thermistors 200 and 200S are provided on the back surface 110m of the heater 110. The thermistor 200 is disposed at a position overlapping a region through which sheets of all sizes that can be used by the fixing unit 6 pass, and the control unit 32 (see FIG. 1) energizes the resistive heating element 11b with an AC current, so that the temperature of the thermistor 200 becomes a desired temperature.

On the other hand, the thermistor 200S is disposed at a position away by 198 mm from the reference position ZP of the sheet P in the longitudinal direction LD on the left side so as to overlap the sheet non-passage range when A5 paper is printed. The thermistor 200S has a role of monitoring a temperature of the sheet non-passage region when narrow paper such as A5 paper is printed. When the temperature of the thermistor 200S becomes higher than or equal to a predetermined temperature, the control unit 32 performs control to stop the printing or to increase an interval at which the sheets P are fed.

In the present modification, the sheet non-passage range in the fixing nip NF when a sheet P having a narrow width is conveyed is only the left side in FIGS. 23 to 25, and the heat conducting member 18 is disposed to correspond to such a sheet non-passage range, thereby making it possible to configure the heat conducting member 18 to be short. The connecting portions 201a of the printed wires 201 for feeding power to the respective thermistors 200 and 200S are disposed outside the resistive heating element 11b and the heat conducting member 18 in the longitudinal direction LD. Each lead wire 21 is bonded to each connecting portion 201a by means of welding, pressure contact, brazing, ultrasonic bonding, or the like, and the lead wire 21 is connected to the control unit 32 (see FIG. 1). The lead wire 21 is connected to the control unit 32 (see FIG. 1) through the hole 12h provided in the first seating surface 12b of the heater holder 12. Similarly to the connecting portion 201a, the hole

12h is disposed outside the resistive heating element 11b and the heat conducting member 18 in the longitudinal direction LD.

As a result, there is no need to perform processing for forming a hole or the like for allowing the lead wire 21 to pass through the heat conducting member 18 or the first seating surface 12b of the heater holder 12 in a heat generating region of the resistive heating element 11b, making it possible to improve the temperature leveling-out effect of the heat conducting member 18 in the heat generating region of the heater 110.

In the present modification, the insulating layer 24 is also provided in a range where the heat conducting member 18 is not present in the longitudinal direction LD and in the short direction SD. However, in a range where the heat conducting member 18 is not present, the insulating layer 24 may not be provided because there is no risk of short circuit or leakage. In this case, it is preferable to devise a shape of the second seating surface 12c of the heater holder 12 so that the thermistor 200 and the printed wire 201 do not interfere with the heater holder 12.

As described above, in the present modification, also in the fixing unit 6 that conveys the sheet P on a one-side basis, the connecting portion 201a and the hole 12h are provided outside the heat conducting member 18 in the longitudinal direction LD. As a result, there is no need to perform processing for forming a hole or the like for allowing the lead wire 21 to pass through the heat conducting member 18 or the first seating surface 12b of the heater holder 12, making it possible to improve the temperature leveling-out effect of the heat conducting member 18 in the heat generating region of the heater 110.

Needless to say, in the configuration described in the third embodiment (including the first and second modifications thereof) as well, a deviation of the heat conducting member 18 in the longitudinal direction LD can be reduced by providing the protrusions 11d and 11e described in the first embodiment on the back surface 11m of the heater 11.

Fourth Embodiment

Next, the fourth embodiment of the present invention will be described. In the fourth embodiment, a bonding portion 12f is provided in the heater holder 12 according to the first embodiment. Therefore, a configuration thereof similar to that of the first embodiment will not be illustrated or will be described with the same reference signs being given in the drawings.

Conventionally, in order to easily dispose of a jammed sheet, there has been known a configuration in which a pressure of a load applied to the fixing film unit 19 is temporarily reduced. If the pressure on the fixing film unit 19 is reduced in the configuration according to the first embodiment, the heater 11 may rise up from the heater holder 12. As a result, there is a possibility that the heat conducting member 18 may get between the protrusions 11e and 11d or the protrusions 11f and 11g (see FIG. 9A) and the first seating surface 12b of the heater holder 12. In addition, when the pressure on the fixing film unit 19 is reduced in the configuration according to the third embodiment, if the heater 11 rises up from the heater holder 12, the position of the connecting portion 201a moves, and accordingly, there is a possibility that a load may be applied to the lead wire 21, and the lead wire 21 may come off the connecting portion 201a.

In order to cope with such a problem, for example, a configuration in which the heater 11 is bonded to the heater

holder 12 using a heat-resistant adhesive is effective. If the heater 11 is bonded to the heater holder 12, the heater 11 does not rise up from the heater holder 12, suppressing an occurrence of the phenomenon as described above.

5 The fourth embodiment of the present invention will be described as an example of a configuration in which the heater 11 is bonded to the heater holder 12 using a heat-resistant adhesive. FIG. 26 is a perspective view illustrating the heater holder 12 according to the present embodiment, and is a perspective view illustrating the vicinity of the region CP of FIG. 8.

10 As illustrated in FIG. 26, the heater holder 12 according to the present embodiment has a plurality of bonding portions 12f on the second seating surface 12c. The heater 11 abuts on the second seating surface 12c serving as an 15 abutment surface. The plurality of bonding portions 12f are arranged side by side in the longitudinal direction LD, and a heat-resistant adhesive is applied to the bonding portions 12f to bond the back surface 11m (see FIG. 8) of the heater 11 to the second seating surface 12c of the heater holder 12.

20 As the heat-resistant adhesive, a material that is inexpensive and can be easily applied while having heat resistance, for example, a moisture-curable silicone rubber or a thermosetting silicone rubber is used. By bonding the back 25 surface 11m of the heater 11 to the second seating surface 12c of the heater holder 12 using a silicone rubber having elasticity even after the heat-resistant adhesive is cured, even when the temperature repeatedly rises and drops and the heater 11 and the heater holder 12 are deformed due to 30 thermal expansion, a bonding surface can follow the deformation, thereby preventing the adhesive from being peeled off. In the present embodiment, KE-3417 (manufactured by Shin-Etsu Silicone Co., Ltd.), which is a moisture-curable 35 silicone rubber, was used as an example of the heat-resistant adhesive.

Next, a detailed shape of the bonding portion 12f will be 40 described with reference to FIGS. 27A to 27C. Since the plurality of bonding portions 12f are formed in the same shape, only one bonding portion 12f will be described. FIG. 27A is a plan view illustrating a bonding portion 12f. FIG. 27B is a cross-sectional view illustrating a cross section taken along line 27B-27B of FIG. 27A, and FIG. 27C is a 45 cross-sectional view illustrating a cross section taken along line 27C-27C of FIG. 27A. Note that FIG. 27B illustrates a cross section of the bonding portion 12f passing through the center CTR and extending in the longitudinal direction LD and in the thickness direction TD, and FIG. 27C illustrates a cross section of the bonding portion 12f passing through the center CTR and extending in the short direction SD and the thickness direction TD.

50 The bonding portion 12f has an adhesive application surface 12f1 serving as an application surface and grooves 12f2 and 12f3. The adhesive application surface 12f1 is a portion that is bonded to the heater 11 via the heat-resistant adhesive, and has a counterbore shape provided in the second seating surface 12c. In the present embodiment, the adhesive application surface 12f1 is a circular counterbore having a diameter of 4 mm and a depth of 0.15 mm. The adhesive application surface 12f1 may not be a counterbore but may be the same surface as the second seating surface 12c.

55 The grooves 12f2 and 12f3 are provided so as to surround the periphery of the adhesive application surface 12f1. In the present embodiment, the grooves 12f2 and 12f3 have a width of 1 mm, and the bonding portion 12f has a circular shape with an overall diameter of 6 mm. The groove 12f2 serving 60 as a first groove is provided near the center of the second

seating surface $12c$ in the short direction, and the groove $12/2$ has a depth of 0.6 mm from the second seating surface $12c$. The groove $12/3$ serving as a second groove is provided on the end side in the short direction SD of the second seating surface $12c$ with respect to the groove $12/2$. The groove $12/3$ has a depth of 1.0 mm from the second seating surface $12c$, and is deeper than the groove $12/2$. In other words, the groove $12/3$ is disposed at a position closer to one end $12cl$ as an end of the second seating surface $12c$ than the groove $12/2$ in the short direction SD, and is formed deeper than the groove $12/2$. It can also be said that the groove $12/3$ has a larger volume than the groove $12/2$.

Although the heat-resistant adhesive is applied onto the adhesive application surface $12/1$ by a predetermined amount, the heat-resistant adhesive may overflow from the adhesive application surface $12/1$ due to the process capability of the adhesive dispenser. If the overflowing heat-resistant adhesive overflows onto the second seating surface $12c$, the heat-resistant adhesive may flow around from an end surface (a side surface in the short direction SD) of the substrate $11a$ of the heater 11 to the front surface of the heater 11 , hindering a sliding rotation of the fixing film 13 . In particular, if the heat-resistant adhesive overflows in the short direction SD of the heater 11 , there is a high possibility that the heat-resistant adhesive may flow around onto the front surface of the heater 11 because the distance to the end surface of the substrate $11a$ is short.

In order to prevent the heat-resistant adhesive from flowing around onto the front surface of the heater 11 as described above, the grooves $12/2$ and $12/3$ are provided so as to surround the adhesive application surface $12/1$ in the present embodiment. The heat-resistant adhesive that has overflowed from the adhesive application surface $12/1$ falls into the grooves $12/2$ and $12/3$, making it difficult to overflow onto the second seating surface $12c$.

The deeper the grooves $12/2$ and $12/3$, the larger the space created for the overflowing heat-resistant adhesive to be released, making it more difficult for the heat-resistant adhesive to overflow onto the second seating surface $12c$. However, if the grooves $12/2$ and $12/3$ are too deep, the stiffness of the heater holder 12 decreases, and accordingly, it is not possible to maintain the stiffness required for the heater holder 12 .

Therefore, in the present embodiment, concerning the groove $12/2$ of which the distance to the end surface (the side surface in the longitudinal direction LD) of the substrate $11a$ is relatively long with a low possibility that the heat-resistant adhesive may flow around onto the front surface of the heater 11 , the depth of the groove $12/2$ is small to secure the stiffness of the heater holder 12 . On the other hand, concerning the groove $12/3$ of which the distance to the end surface (the side surface in the short direction SD) of the substrate $11a$ is relatively short with a high possibility that the heat-resistant adhesive may flow around onto the front surface of the heater 11 , the depth of the groove $12/3$ is deeper than the groove $12/2$. As a result, while the heat-resistant adhesive is allowed to overflow from the bonding portion $12f$ in the longitudinal direction LD to some extent, the heat-resistant adhesive is prevented from overflowing from the bonding portion $12f$ in the short direction SD, and the heat-resistant adhesive is suppressed from flowing around onto the front surface of the heater 11 .

As described above, by forming the groove $12/3$ deeper than the groove $12/2$, it is possible to suppress the heat-resistant adhesive from flowing around onto the front surface of the heater 11 while securing the stiffness of the heater holder 12 .

First Modification of Fourth Embodiment

Next, a first modification of the fourth embodiment will be described. In the first modification of the fourth embodiment, the shape of the bonding portion $12f$ according to the fourth embodiment is changed. Therefore, a configuration thereof similar to that of the fourth embodiment will not be illustrated or will be described with the same reference signs being given in the drawings.

In the fourth embodiment, the entire bonding portion $12f$ is formed in a circular shape, but the bonding portion $12f$ is not limited thereto. FIG. 28A is a plan view illustrating an elliptical bonding portion $12f$. FIG. 28B is a plan view illustrating an oval bonding portion $12f$. FIG. 28C is a plan view illustrating a square bonding portion $12f$. FIG. 28D is a plan view illustrating a rectangular bonding portion $12f$. FIG. 28E is a plan view illustrating another rectangular bonding portion $12f$.

As illustrated in FIGS. 28A to 28E, the bonding portion $12f$ may have an elliptical shape, an oval shape, a square shape, a rectangular shape, or the like. In this case, the shape of the entire bonding portion $12f$ and the shape of the adhesive application surface $12/1$ do not need to match each other. For example, as illustrated in FIG. 28E, the adhesive application surface $12/1$ may be formed in a square shape, and the entire bonding portion $12f$ may be formed in a rectangular shape.

As described above, by appropriately changing the shape of the bonding portion $12f$, it is possible to arrange the bonding portion $12f$ in accordance with the shape of the surroundings in which the bonding portion $12f$ is to be placed, and it is possible to improve the degree of freedom in design.

Second Modification of Fourth Embodiment

Next, a second modification of the fourth embodiment will be described. In the second modification of the fourth embodiment, the grooves of the bonding portion $12f$ according to the fourth embodiment are sorted by three depths. Therefore, a configuration thereof similar to that of the fourth embodiment will not be illustrated or will be described with the same reference signs being given in the drawings.

FIG. 29A is a plan view illustrating a bonding portion $12f$. FIG. 29B is a cross-sectional view illustrating a cross section taken along line 29B-29B of FIG. 29A, FIG. 29C is a cross-sectional view illustrating a cross section taken along line 29C-29C of FIG. 29A, and FIG. 29D is a cross-sectional view illustrating a cross section taken along line 29D-29D of FIG. 29A.

As illustrated in FIGS. 29A to 29D, in the present modification, a partial portion of the groove $12/2$ according to the fourth embodiment is replaced with a groove $12/4$. The groove $12/4$ has a depth of 0.8 mm from the second seating surface $12c$, and is deeper than the groove $12/2$ and shallower than the groove $12/3$. That is, using the second seating surface $12c$ as a reference, the depths of the adhesive application surface $12/1$, the groove $12/2$, the groove $12/4$, and the groove $12/3$ increase in this order.

In the present modification, the grooves of the bonding portion $12f$ are sorted by three depths, but may be sorted by four or more depths.

Third Modification of Fourth Embodiment

Next, a third modification of the fourth embodiment will be described. In the third modification of the fourth embodi-

ment, the shape of the groove 12/3 of the bonding portion 12f according to the fourth embodiment is changed. Therefore, a configuration thereof similar to that of the fourth embodiment will not be illustrated or will be described with the same reference signs being given in the drawings.

FIG. 30A is a plan view illustrating a bonding portion 12f. FIG. 30B is a cross-sectional view illustrating a cross section taken along line 30B-30B of FIG. 30A, FIG. 30C is a cross-sectional view illustrating a cross section taken along line 30C-30C of FIG. 30A, and FIG. 30D is a cross-sectional view illustrating a cross section taken along line 30D-30D of FIG. 30A.

As illustrated in FIGS. 30A to 30D, the groove 12/3 according to the third modification of the fourth embodiment has a gradient on a bottom surface 12/3a thereof, continuously changing the depth of the groove. In the present modification, the bottom surface 12/3a is inclined downward toward the outside in the short direction SD. In other words, the bottom surface 12/3a is inclined downward as being farther away from the center CTR of the bonding portion 12f in the short direction SD. Also, the groove 12/3 has a larger volume than the groove 12/2.

Note that the depth of the groove 12/3 may be infinite, that is, the groove 12/3 may be a through hole. Further, in the present fourth embodiment, the adhesive application surface 12/1 is formed as a smooth flat surface, but the adhesive application surface 12/1 may be subjected to embossing or knurling to have irregularities. By forming the irregularities on the adhesive application surface 12/1, the surface area of the adhesive application surface 12/1 increases, such that the adhesive strength using the heat-resistant adhesive can be improved. In addition, in the present fourth embodiment, the bonding portion 12f is provided in the vicinity of the region CP (see FIG. 8) of the second seating surface 12c of the heater holder 12, but the bonding portion 12f is not limited thereto. The bonding portion 12f may be disposed anywhere on the second seating surface 12c as long as it is a region where the heat conducting member 18 does not exist in the longitudinal direction LD and a region facing the heater 11 in the thickness direction TD.

Needless to say, in the configuration described in the fourth embodiment (including the first to third modifications thereof) as well, a deviation of the heat conducting member 18 in the longitudinal direction LD can be reduced by providing the protrusions 11d and 11e described in the first embodiment on the back surface 11m of the heater 11.

Other Embodiments

In any of the embodiments described above, the heater 11 is in direct contact with the fixing film 13, but the heater 11 is not limited thereto. For example, a sheet material having high thermal conductivity such as iron alloy or aluminum may be provided between the heater 11 and the fixing film 13, and the heater 11 may abut on an inner peripheral surface of the fixing film 13 via the sheet material. Even though such a sheet material is provided between the heater 11 and the fixing film 13, the fixing film 13 is interposed between the pressure roller 17 and the heater 11.

In any of the embodiments described above, the heater is not limited to the ceramic heater, and a halogen heater or the like can also be applied.

While the present invention has been described with reference to exemplary embodiments, it is to be understood that the invention is not limited to the disclosed exemplary embodiments. The scope of the following claims is to be

accorded the broadest interpretation so as to encompass all such modifications and equivalent structures and functions.

This application claims the benefit of Japanese Patent Application No. 2023-130536, filed Aug. 9, 2023, which is hereby incorporated by reference herein in its entirety.

What is claimed is:

1. A fixing unit comprising:
a rotary member having a cylindrical shape;
a pressure member configured to form a fixing nip that

fixes a toner image onto a sheet together with the rotary member;
a heater disposed in an internal space of the rotary member, the heater including a substrate, and a heating element provided on the substrate and configured to heat the rotary member by being energized;
a heater holder configured to hold the heater; and
a heat conducting member disposed between the heater and the heater holder,

wherein the fixing nip conveys the sheet in a direction

parallel to a short direction perpendicular to a longitudinal direction of the heater,

the heater includes a protrusion extending toward the heater holder from a surface, of the heater, provided on a side opposite to the fixing nip,

the protrusion faces the heat conducting member in the longitudinal direction and is disposed so as not to overlap the heat conducting member as viewed in the short direction,

the heater holder includes:

an abutment surface on which the heater abuts; and
a bonding portion provided on the abutment surface to which an adhesive is applied to bond the heater and heater holder,

the bonding portion includes:

an application surface to which the adhesive is applied; and

first and second grooves surrounding a periphery of the application surface, and

the second groove is disposed outside the first groove in the short direction, and has a larger volume than the first groove.

2. The fixing unit according to claim 1, wherein a movement of the heat conducting member in the longitudinal direction is restricted in a case where the heat conducting member abuts against the protrusion.

3. The fixing unit according to claim 1, wherein the protrusion is a first protrusion, and

the heater further includes a second protrusion extending from the surface toward the heater holder, and

the second protrusion is disposed on a side opposite to the first protrusion across the heat conducting member in the longitudinal direction while facing the heat conducting member, and is disposed so as not to overlap the heat conducting member as viewed in the short direction.

4. The fixing unit according to claim 3, wherein the first protrusion and the second protrusion do not simultaneously abut on the heat conducting member while the sheet is being conveyed by the fixing nip.

5. The fixing unit according to claim 3, wherein the heat conducting member is configured to be movable between the first protrusion and the second protrusion in the longitudinal direction with respect to the heater.

6. The fixing unit according to claim 3, wherein the heater further includes a third protrusion and a fourth protrusion, the third protrusion and the fourth protrusion extending from the surface toward the heater holder, and

31

the third protrusion and the fourth protrusion are disposed on opposite sides in the short direction across the heat conducting member while facing the heat conducting member, and are disposed so as not to overlap the heat conducting member as viewed in the longitudinal direction.

7. The fixing unit according to claim 1, wherein the heat conducting member is made of a metal material.

8. The fixing unit according to claim 1, wherein the heat conducting member has the same length as the heating element in the longitudinal direction.

9. The fixing unit according to claim 1, wherein the heat conducting member is shorter than the heating element in the longitudinal direction.

10. The fixing unit according to claim 1, wherein the heat conducting member has a higher thermal conductivity than the substrate.

11. The fixing unit according to claim 1, further comprising:

a temperature detection unit provided on the surface of the heater, and configured to detect a temperature of the heater;

a wiring pattern provided on the surface of the heater and electrically connected to the temperature detection unit; and

an insulating layer disposed between the surface of the heater and the heat conducting member.

12. The fixing unit according to claim 11, wherein at least a part of the temperature detection unit and the wiring pattern is covered by the insulating layer.

13. The fixing unit according to claim 11, wherein the insulating layer has an opening at a position corresponding to the temperature detection unit.

14. The fixing unit according to claim 13, wherein the heat conducting member has an opening at a position corresponding to the temperature detection unit.

15. The fixing unit according to claim 13, wherein the heat conducting member has a recess recessed in a direction away from the temperature detection unit, the recess being positioned at a position corresponding to the temperature detection unit.

16. The fixing unit according to claim 11, further comprising a conductive wire connected to the wiring pattern, wherein each of the insulating layer and the heat conducting member has an opening through which the conductive wire is wired.

32

17. The fixing unit according to claim 11, wherein the insulating layer is formed in a sheet shape.

18. The fixing unit according to claim 1, further comprising:

a temperature detection unit provided on the surface of the heater, and configured to detect a temperature of the heater;

a wiring pattern provided on the surface of the heater and electrically connected to the temperature detection unit; and

a conductive wire connected to the wiring pattern at a connecting portion,

wherein the connecting portion is disposed outside the heat conducting member in the longitudinal direction.

19. The fixing unit according to claim 18, wherein the heater holder has a hole through which the conductive wire passes, and

the hole is disposed on the same side as the connecting portion with respect to the heat conducting member in the longitudinal direction.

20. The fixing unit according to claim 18, wherein the heater includes a contact with which the heater is energized, and

the connecting portion is disposed on a side opposite to the contact with the heat conducting member interposed therebetween in the longitudinal direction.

21. The fixing unit according to claim 1, wherein the second groove is formed deeper than the first groove with respect to the application surface.

22. The fixing unit according to claim 1, wherein the second groove is closer to an end of the abutment surface than the first groove in the short direction.

23. The fixing unit according to claim 1, wherein the adhesive has elasticity after being cured.

24. The fixing unit according to claim 1, wherein the rotary member is a film,

the heater nips the film together with the pressure member, and

the toner image formed on the sheet is fixed onto the sheet by being heated through the film at the fixing nip.

25. An image forming apparatus comprising:

an image forming unit that forms a toner image on a sheet; and

the fixing unit according to claim 1 configured to fix the toner image formed, on the sheet, by the image forming unit onto the sheet.
